Patented Mar. 31, 1959

184,774

ARROW QUIVER

Daniel J. Smith, Racine, Wis.

Application October 24, 1957, Serial No. 48,228

Term of patent 14 years

(Cl. D30—1)

Fig. 1 is a front perspective view of an arrow quiver showing my new design.

Fig. 2 is a left side elevational view of the quiver shown in Fig. 1.

Fig. 3 is a top plan view of the quiver shown in Fig. 1.

Fig. 4 is a bottom plan view of the quiver shown in Fig. 1.

I claim:

The ornamental design for an arrow quiver, substantially as shown.
